(57) **CLAIM**

The ornamental design for a fuel pressure regulator, as shown and described.

DESCRIPTION

FIG. 1 is an isometric view of the fuel pressure regulator, showing the mounting bracket and the fuel conduit fittings mounted to the body of the regulator;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and

FIG. 8 is an isometric view of the fuel pressure regulator of FIG. 1, with the fuel conduit fittings and the mounting bracket removed therefrom;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.
